ABSTRACT

A melt chlorination process which comprises chlorinating C_1 to C_{10} hydrocarbons and their incompletely chlorinated derivatives with a melt comprising iron chloride and alkali metal chloride(s) by dispersing the material to be chlorinated in the melt whereby said material is chlorinated by the melt, wherein certain alkali metals, proportions thereof, and process conditions are utilized. Various process parameters are controlled to provide desired product selectivity. In particular, ethylene, ethylene dichloride and/or vinyl chloride are chlorinated to selectively produce at least 50 mole percent of dichloroethylene.

PRODUCTION OF DICHLOROETHYLENE USING MELT CHLORINATION PROCESS

CROSS-REFERENCES TO RELATED APPLICATIONS

This is a continuation-in-part of Ser. No. 740,672, filed June 27, 1968 now abandoned.

BACKGROUND OF THE INVENTION

Many methods have been proposed in the prior art for randomly or selectively producing chlorinated hydrocarbons from hydrocarbons and/or chlorohydrocarbons in processes involving modified Deacon-type chlorination procedures. In processes of this character, oxygen, the hydrocarbon and/or chlorohydrocarbon to be chlorinated, and chlorine or HCl as the chlorinating agent, are brought into contact at elevated temperatures with a metal halide catalyst, usually a copper chloride-containing catalyst. Where HCl is utilized as the feed material, it is believed that a preliminary oxidation of the HCl takes place resulting in the formation of water and elemental chlorine. The chlorine produced then reacts with the hydrocarbon and/or chlorohydrocarbon feed to produce further quantities of HCl and a chlorinated derivative of the feed material. When chlorine is utilized as the chlorinating agent, it is believed that an initial chlorination of the hydrocarbon and/or chlorohydrocarbon takes place which generates HCl. The HCl thus generated is converted by the conventional Deacon reaction to chlorine and water.

In recent years considerable emphasis has been laid on fluid bed processes for conducting such oxychlorination procedures since the reactions involved are highly exothermic and the removal of heat usually becomes a problem of considerable moment. In conducting fluidized bed oxychlorination procedures of this type, however, many difficulties are encountered. For example, in some instances the fluidized bed does not provide sufficient contact with the initial feed to produce complete chlorination or high yields of substitutive chlorination. Also, the fluidized bed becomes hard to handle in high temperature chlorination procedures. Consequently, many methods have been devised for providing adequate cooling of the fluidized bed catalyst particles employed during reaction. Various carriers have been tested to determine the best materials from the standpoint of thermal conductivity, lack of attrition during fluidization, and other similar considerations in order to arrive at a material suitable for use as a support for the catalyst material employed during the chlorination reaction. Product recovery from the reaction zones without injuring the catalyst particles is also another problem encountered in this area. Many of the gas mixtures fed are highly explosive under certain conditions so that proper mixing of them is an extremely important factor. In addition, corrosion of materials of construction utilized in forming the reactors involved, and the selection of the proper size of the reactors for the purpose of providing maximum productivity are also problems. It has also been found that when conducting these processes in large reactors (two feet or more in diameter), a considerable sacrifice in overall efficiency of the process contemplated is experienced.

The commercial success of these processes is due largely to the demand for halogenated compounds containing from 1 to 10 carbon atoms; however, there is a great need for improvement of these processes. For ex-

ample, it would be highly desirable to reduce the contact time normally associated with fixed bed operations, while eliminating the difficulties associated with fluidized solids operation such as catalyst attrition and

5 catalyst vaporization which appears to be more pronounced with highly active catalysts. While the moving bed solves some of these difficulties, it is not without its own particular problems such as those derived from the mechanical transportation of catalysts throughout a 10 zone and the existence of "hot spots" in the catalyst bed. The heat of reaction generated on the surface of the solid permits direct oxidation of the hydrocarbon and/or chlorohydrocarbon to produce undesirable oxides of carbon.

15 The more active metal halide catalysts such as, copper chloride, are more volatile at required halogenation temperature and thus, it is difficult to retain the catalyst in the system and maintain the activity of the catalyst mass over an extended period of time. In such systems

20 the volatilized catalyst must be recovered by condensation or other troublesome methods and returned in a supported state to the reaction zone. Thus, the economics of operating with fluidized catalysts is poor in spite of the fact that such a system provides better temperature control and higher yield of product for a given period of operation.

25 Therefore, it is readily apparent that a new chlorination process is needed which overcomes the above difficulties by providing a more economic and commercially feasible chlorination process. Additionally, a better chlorination process is desired to provide improved contact between the hydrocarbon and/or chlorohydrocarbon and chlorinating agents in conjunction with 30 good temperature control of the reaction zone. Furthermore, a selective chlorination process (i.e., a process that produces predominantly one specific chlorinated product in high yields) is in great demand throughout the industry.

SUMMARY OF THE INVENTION

35 This invention relates to a chlorination process which comprises chlorinating a material selected from the group consisting of ethylene, ethylene dichloride, vinyl chloride and mixtures thereof to produce a chlorinated product which contains at least 50 mole percent of dichloroethylene, in a reaction zone, which is essentially free of elemental chlorine, at a temperature within the range of from 200°-450°C., by means of a melt comprising iron chloride and alkali metal chloride(s) by dispersing the material to be chlorinated in the melt, the melt being the continuous phase, whereby said material is chlorinated by the melt; withdrawing a gaseous effluent from the reaction zone which contains unreacted starting material and the resulting chlorinated hydrocarbon products and recovering the chlorinated hydrocarbon products from the effluent as the products of the process; and regenerating the melt with a regenerating system selected from the group consisting of a chlorine-containing gas and a combination of an oxygen-containing gas and hydrogen chloride, wherein:

40 a. the alkali metal chloride is selected from the group consisting of sodium chloride, potassium chloride, a mixture thereof, a mixture of sodium chloride and no more than 20 mole percent lithium chloride, a mixture of potassium chloride and no more than 20 mole percent lithium chloride, and a mix-

- ture of sodium chloride, potassium chloride and no more than 20 mole percent lithium chloride;
- b. the mole ratio of alkali metal chloride(s) to iron chloride is from about 0.5:1 to about 2:1; and
- c. 60-90 mole percent of the iron chloride is maintained as ferric chloride.

BRIEF DESCRIPTION OF THE DRAWING

For a more complete understanding of the invention reference is made to the accompanying drawing which illustrates suitable apparatus for carrying out the invention.

DESCRIPTION OF THE PREFERRED EMBODIMENTS

The preferred process of this invention involves chlorinating ethylene, ethylene dichloride, vinyl chloride or mixtures thereof, to produce high yields of dichloroethylene by contacting the ethylene, ethylene dichloride, vinyl chloride or mixtures thereof with the above-described melt. In addition, the process of this invention is equally applicable to the chlorination of these C_2 materials together with minor amounts of many other C_1 to C_{10} hydrocarbons and/or their incompletely chlorinated derivatives, and more specifically, to C_2 to C_{10} unsaturated hydrocarbons and their chlorinated derivatives. However, since the desired ultimate product must contain at least 50 mole percent of dichlorethylene, the "minor amounts" of other materials to be chlorinated must be such as not to change this chlorinated product requirement.

Since ethylene is one of the preferred starting materials, the discussion throughout the specification is directed to the chlorination of ethylene, without intending to limit the scope of this invention to ethylene.

It is pointed out that when chlorinating ethylene, the preferred process of this invention effects a high selectivity toward dichloroethylene. The terminology "high selectivity" is intended to designate that at least 50 mole percent of the chlorinated product is dichloroethylene (DCE), with a preferred selectivity being at least 70 percent DCE.

The preferred process of this invention is also directed to producing "high yields" of chlorinated hydrocarbons. The terminology "high yields" means that a high percentage (at least 70 percent) of the starting material is converted to chlorinated hydrocarbons, with the yield losses being represented by CO , CO_2 and any other oxygen-containing by-products. More specifically "high yields" of dichloroethylene are desired with the yield losses being CO , CO_2 and any other oxygen-containing by-products. In order to achieve high yields, the melt composition (e.g., KCl , etc.), temperature, HCl partial pressure and oxide content must be optimized within the teachings of this invention.

Generally as ethylene is chlorinated, with the progressive addition of chlorine and splitting out of HCl , the chlorination products are as follows: ethylene dichloride (1,2-dichloroethane), vinyl chloride, 1,1,2-trichloroethane, dichloroethylene (DCE), tetrachloroethane, trichloroethylene, pentachloroethane, perchloroethylene, and hexachloroethane. The employment of the various process parameters of this invention results in a high selectivity of product to at least 50 percent dichloroethylene in the preferred embodiment, with smaller amounts of the incompletely chlorinated derivatives (e.g., ethylene dichloride, vinyl chloride, and

1,1,2-trichloroethane) being produced; very minor amounts of the more completely chlorinated derivatives (e.g., tetrachloroethane, trichloroethylene, pentachloroethane, perchloroethylene and hexachloroethane) may also be produced.

The chlorination process of this invention involves the use of a particular melt which contains certain metal chlorides in critical proportionate amounts to produce the desired selectivity of product. The essential components of the melt composition are ferric chloride and alkali metal chloride(s). The ferric chloride is considered to have at least two functions; it acts as a chlorinating agent and also as a dehydrohalogenating agent. The function of the alkali metal chloride(s) is to reduce the vapor pressure of ferric chloride and also to reduce the chlorinating power of the ferric chloride in order that the chlorination product can be stopped selectively, for example, in the case of ethylene, at dichloroethylene. The alkali metal chloride also is necessary to produce a melt and to moderate the dehydrohalogenating (HCl cracking) reaction.

Since ferric chloride acts as the chlorinating agent, there must be some ferric chloride present in the melt at all times. Therefore, one of the essential features of this invention is that about 60-90 mole percent of the iron chloride be maintained as ferric chloride.

Ideally, it is desirable to have only $FeCl_3$ present since this is the chlorinating agent. However, ferric chloride a solid which melts at 300°C. and then sublimes at almost the same temperature, has an impractical operating range as the sole composition in a melt. Therefore, an alkali metal chloride is added to form a complex salt ($MFeCl_4$) with $FeCl_3$ to thereby extend the operating range of the melt. Sodium chloride, for example, and $FeCl_3$ form a known compound, $NaFeCl_4$, which melts at about 145°C. and has a low vapor pressure at temperatures even about 400°C. It has been observed that the potassium complex salt ($KFeCl_4$) forms a more stable complex than $NaFeCl_4$ and $LiFeCl_4$. Thus, the presence of the alkali metal chloride(s) moderates the chlorinating ability of the melt. While not intending to be bound by any particular theory, the chlorination reaction taking place in the melt is interpreted as follows:

However, it is not entirely certain whether the actual chlorination reaction occurs in accordance with the above equation. For example, chlorine radicals may emanate and go directly from the $FeCl_3$ to the hydrocarbon. On the other hand, some free chlorine radicals may randomly contact the hydrocarbon and chlorinate the hydrocarbon. Thus, it is to be understood that it is the combination of all the components acting together in the melt that does the chlorinating.

The above reaction is a reversible reaction. By adding chlorine ($Cl_2 \rightarrow 2Cl$) to a melt containing MCl and $FeCl_2$, the $MFeCl_4$ can be regenerated. Also, as the concentration of MCl is increased up to its solubility limit, the reversible reaction is driven toward the $MFeCl_4$ complex salt and this presumably lowers the concentration of chlorine free radicals. Hence, the extent of hydrocarbon chlorination is decreased. Also, since the amount of uncomplexed $FeCl_3$ is reduced by adding an increased amount of MCl , the dehydrohalogenating power of the melt is reduced and this

in turn favors the production of saturated chlorohydrocarbons.

The alkali chlorides (MCl) that are suitable include KCl, NaCl and LiCl. The presence of these chlorides is necessary to produce a liquid phase with ferric chloride, to depress the volatility of the ferric chloride at operating temperatures and to obtain a ferric chloride-containing melt which will have selective chlorinating power. The alkali chloride (MCl):FeCl₃ ratio should be from 0.5:1 to 2:1 in the preferred DCE process. These are the critical proportions of this invention. Below 0.5 mole alkali chloride per mole of FeCl₃, there is not enough alkali chloride to tie up the FeCl₃ and the FeCl₃ volatilizes out of the reactor. As the amount of MCl is increased to above 2 moles per mole of FeCl₃, the MFeCl₄ salt is more stable and is less able to give off the desired chlorine to chlorinate. The vapor pressure of the chlorine is diminished by too much alkali chloride and an insufficient amount of chlorination is achieved. Also, at ratios of MCl:FeCl₃, the melting point of the melt chloride mixture is too high so that the system becomes too difficult to operate.

The broadest aspects of the invention include the use of KCl, NaCl, RbCl, CsCl and mixtures thereof, in conjunction with iron chloride. The rate and degree of chlorination varies with each chloride; the activity rates are: LiCl>NaCl>KCl. The rate and degree of chlorination can be adjusted by the choice of alkali metal chloride(s) and the amount of alkali metal chloride, which must always be kept within the prescribed limits (i.e., 0.5:1 to 2:1 alkali metal chloride to iron chloride). When chlorinating ethylene to produce dichloroethylene as the desired product, no more than 20 mole percent (0-20 mole percent) of the alkali metal chloride can be LiCl. More than 20 mole percent LiCl will produce major amounts of higher chlorinated products (e.g., symmetrical tetrachloroethane). Thus, rate and degree of chlorination can be optimized by one skilled in the art in accordance with the teachings of this invention.

Alkaline earth metal chlorides (e.g., calcium and barium chlorides) may also be used in the melt, but the alkaline earth metal chlorides are not preferred since they do not adequately depress the volatility of FeCl₃ as is done by the alkali chlorides. The use of the alkaline earth chlorides, however, is within the scope of this invention.

In the broad spirit of this invention, minor amounts of iron chloride may be replaced by CuCl₂ when the higher chlorinated products are also desired (e.g., symmetrical tetrachloroethane, trichloroethylene, perchloroethylene). Thus, while CuCl₂ may be used in the melt, it is not necessary to carry out the process of this invention.

The temperature at which the melt chlorination process of this invention is carried out is generally within the range of 200°-450°C. The temperature range is dependent upon the metal chloride salt mixture which is utilized and the desired product. Lower temperatures may be used where lower chlorination rates are acceptable or where pressures greater than one atmosphere are utilized. The temperature range of 200°-450°C., in the preferred process where ethylene, ethylene dichloride, vinyl chloride or mixtures thereof are used as the starting materials, is the temperature at which a high selectivity to dichloroethylene results, i.e., at least 50 mole percent dichloroethylene. For example, when

ethylene is the starting materials and sodium chloride is used as the alkali chloride metal, the temperature range of 290°-350°C. is preferred. If the temperature is decreased below 290°C., the product mix will contain 5 smaller amounts of dichloroethylene and larger amounts of ethylene dichloride and vinyl chloride. As the reaction temperature is increased, if the process is run above 350°C. and when sodium chloride is used as the alkali metal, the product mix will contain smaller 10 and smaller amounts of dichloroethylene and greater amounts of the higher chlorinated products (e.g., tetrachloroethane, trichloroethylene and perchloroethylene). When potassium chloride is used as the alkali metal chloride, the preferred temperature range is 15 350°-450°C. to produce the high selectivity to dichloroethylene. When 20 mole percent of lithium chloride is used in the alkali metal chloride, mixture, a preferred range is 260°-280°C. Thus, the temperature range for the production of at least 50 mole percent dichloroethylene in 200°-450°C.

The oxidation level of the iron chloride is critical; in the preferred process at least 60 mole percent of the iron should be maintained in the ferric (Fe⁺⁺⁺) state (i.e., at least 60 mole percent FeCl₃). If less than 60 percent of the iron is in the ferric state, chlorination occurs but the rate of chlorination is low. In the case of ethylene, dichloroethylene is not the major product and chlorinated products, such as ethylene dichloride, are produced. The upper limit is not as critical to the extent that some type of chlorinated products are produced; however, the higher oxidation levels (91-100 percent ferric state) generally produce the higher chlorinated products, such as tetrachloroethane and perchloroethylene. The proper oxidation level must be selected in order to obtain the desired product selectivity. Therefore, when dichloroethylene is the desired major product, the oxidation level is from 60-90 mole percent of iron in the ferric state.

The pressure employed in the chlorination process can vary considerably and be as high as 50 atmospheres. A pressure within the range of 1 to 10 atmosphere is preferred. The pressure utilized is restricted by materials of construction and the problems of handling the melt at the high operating temperatures of this invention.

The atmosphere employed in the melt and surrounding the melt, in the preferred chlorination process, is essentially free of any substantial amount of added elemental chlorine. This terminology is intended to exclude the presence or addition of free chlorine to the reaction zone for the purpose of directly chlorinating the hydrocarbon. Since this process involves using the melt itself as the chlorinator, no free elemental chlorine is required or used to directly chlorinate the hydrocarbon. However, the melt itself might give off minor amounts of elemental chlorine through decomposition of the metal chlorides. Also, free chlorine may be added to the reaction zone to regenerate the melt. However, the chlorine, even when premixed with the feed, will preferentially oxidize (chlorinate) the FeCl₂ to FeCl₃ rather than enter into the hydrocarbon chlorination reaction. Therefore, the terminology "atmosphere essentially free of elemental chlorine" is intended to permit the presence, in the reaction zone, of minor amounts of elemental chlorine which are given off by the melt, or used to regenerate, but not the presence or addition of any elemental chlorine, separate

and apart from the melt, which would in fact chlorinate the hydrocarbon.

The hydrocarbons suitable for the chlorination reactions described herein include saturated aliphatics such as methane, ethane, propane, the butanes, and hydrocarbons containing up to 10 carbon atoms; unsaturated aliphatic hydrocarbons, such as ethylene, propylene, the butylenes, butadiene, isopropene and hydrocarbons containing up to about 10 carbon atoms including isomeric types; and aromatically unsaturated hydrocarbons, such as benzene, toluene, xylene, styrene, etc. Also, there incompletely chlorinated derivatives can be used. The terminology "incompletely chlorinated derivatives" is intended to include hydrocarbons containing at least one hydrogen atom which can be replaced by chlorine. For example, vinyl chloride, ethylene dichloride, 1,1,2-trichloroethane, symmetrical and/or unsymmetrical tetrachloroethane, chlorobenzene, etc., can be used as starting materials. Of this group, the preferred hydrocarbons are ethylene, ethylene dichloride and vinyl chloride. Additionally mixtures of all of the above-listed materials can be used as the starting materials (feed stock).

The process of this invention involves providing good contact between the hydrocarbon gas and the melt. An effective method that may be used is to disperse the gas in the body of the melt. The dispersal may be effected by forcing the gas, in the form of fine bubbles, to ascend through the melt, by any known means. Typical means include porous plate, or porous thimbles, a suitable bubbling apparatus of a sparger. A stirring apparatus may also be used. Several stages may be used, with the gas being dispersed into the melt at several different positions in the apparatus, while the melt is passed continuously from one stage to another. An essential requirement is that the hydrocarbon gas be dispersed and finely distributed throughout the melt to provide good contact between the hydrocarbon gas and the melt, and to obtain a reasonable reaction rate. The size or fineness of the bubbles also has an effect on the reaction rate. The reaction rate increases directly with an increase in the fineness of the hydrocarbon gas bubbles, an increase in the amount of agitation utilized to disperse the hydrocarbon gas in the melt, or any increased overall contact of the hydrocarbon gas with the melt. However, the scope of this invention is not intended to be limited to any particular dispersing mechanisms. Comparatively speaking, if slower reaction rates and chlorination rates can be tolerated, there is no necessity for a thorough dispersion of the hydrocarbon gas in the liquid melt as is required in the preferred embodiment of the invention.

The process of this invention can be carried out as follows: the required amounts of each metal salt, in solid form, are mixed together to obtain even distribution of the respective salts in the salt mixture. This salt mixture is added to a reaction vessel where it is heated to a temperature within the range of 200°-450°C. whereby a melt of the salt mixture is obtained. If any of the metal salts were melted separately, various operating problems would arise. For example, if ferric chloride were melted separately, it would vaporize and boil off (e.g., sublime at high temperatures). If the alkali metal salts were melted separately, very high temperatures would be required since they have high melting points. Therefore, by using a mixture of the metal salts, a melt or molten solution of the metal salts can be

readily obtained at the operating temperatures of this process.

Then ethylene (or any other suitable hydrocarbon or chlorohydrocarbon) is fed to the reaction vessel through any appropriate inlet means. It is a matter of choice and designing skill to decide whether the ethylene enters through the side, top or bottom of the reaction vessel. It is preferred however, that the ethylene enter the reaction vessel near the bottom to give the ethylene a longer contact time with the melt. The ethylene is chlorinated and the chlorinated hydrocarbon reaction products, containing at least 50 percent dichloroethylene, begin to vaporize and rise to the top of the reaction vessel. An outlet is provided, usually at the top of the reaction vessel, where the reaction products can be drawn off; a condensation system, and possibly a scrubber system, could also be provided to recover and/or recycle any unreacted ethylene. The above-described process is essentially a batch-type process; when the oxidation level of the iron chloride drops below the point where 60 percent of it is in the ferric chloride state, this batch process would not chlorinate to the desired high selectivity and high yield of dichloroethylene. The batch process would have to be stopped in order to regenerate the melt to at least the 60 percent ferric chloride level. A suitable batch operation can be carried out by alternatively chlorinating the hydrocarbon (e.g., ethylene), and then regenerating the melt with a chlorine-containing gas or a combination of an oxygen-containing gas and hydrogen chloride prior to the next chlorination run.

The preferred regenerating system comprises a combination of an oxygen-containing gas and hydrogen chloride. This includes the use of mixtures of an oxygen-containing gas and HCl as well as the stepwise use of an oxygen-containing gas and HCl (and vice versa). Any regenerating procedures involving the use of an oxygen-containing gas and hydrogen chloride are applicable.

The terminology "a chlorine-containing gas" includes free elemental chlorine, a mixture of chlorine and oxygen, a mixture of chlorine and hydrogen chloride, and mixtures of chlorine and any other gases which are compatible with the chlorination system. The terminology "an oxygen-containing gas" encompasses free elemental oxygen and mixtures of oxygen and other gases which are compatible with the chlorination system. Air is an economical oxygen-containing gas which can be used.

The preferred process of this invention is a continuous process whereby the melt is continually chlorinating ethylene, being regenerated, and/or recycled. The continuous process of this invention can be operated as either a single-stage operation or a multi-stage operation. In a single-stage continuous process, one reaction vessel is used. While the chlorination is taking place and the ferric chloride is being reduced to ferrous chloride, a chlorine-containing gas or a mixture of an oxygen-containing gas and hydrogen chloride are added to regenerate the melt. Thus, the ethylene is continuously chlorinated by the melt and drawn off in high yields of dichloroethylene at the same time that the melt is being regenerated to provide the required ferric chloride to chlorinate the ethylene. If a chlorine-containing gas is added to regenerate the melt, preferably the chlorine will be supplied in a separate section or zone of the reaction vessel so that the atmosphere in the reaction

zone is essentially free of any substantial amount of elemental chlorine. A typical reaction vessel might contain a central conical section for reacting the hydrocarbon with the melt and a separate side section between the conical section and the walls of the vessel for regeneration of the reduced melt.

The multi-stage continuous process requires use of two or more vessels or reaction zones. The first vessel would be the reaction vessel in which the actual chlorinating is done. The reduced melt containing ferrous chloride would then be pumped to another vessel to be oxidized and thereby regenerated to the ferric state. Into the second and any succeeding vessels is introduced a combination of an oxygen-containing gas (e.g., air) and HCl or a chlorine-containing gas. Also, any by-product water may be removed from the melt in the regeneration zone or in a separate zone. The regenerated melt containing ferric chloride would then be recycled to the original reaction vessel to chlorinate the unchlorinated ethylene.

The chlorination reaction occurring in the reactor may be represented by the following equation (neglecting the role of MCl):

The regeneration reactions can be represented by the following equations:

The amount of oxygen absorbed by the melt is controlled by the rate of passage of the oxygen-containing gas over and through the melt in the regeneration contact zone(s), the pressure of the oxygen-containing gas, the length of the contact zone and the efficiency of the overall regeneration system. Moderate pressures generally give rapid and efficient absorption of oxygen in the melt although operations at atmospheric pressure give satisfactory results. Air pressures between 1 and 50 atmospheres may be employed, however, the preferred range is between 1 and 10 atmospheres. When air is utilized as the gas, absorption of from 35 to 75 percent of the oxygen from the contacting air is readily obtainable. In general, it is not practical to attempt to remove all the oxygen from the air passing through the regeneration zone.

An alternative regeneration reaction is as follows:

The melt utilized in the process of this invention may optionally contain other ingredients. Iron oxide (Fe₂O₃) may be added to the melt in quantities which saturate the melt with iron oxide. In terms of quantity, this is a very small amount (e.g., less than 5 mole percent of the melt) since this oxide is very insoluble in the melt system. At melt temperatures below 350°C., Fe₂O₃ is believed to equilibrate with FeCl₃ to form FeOCl as shown by the following equation:

Therefore, both Fe₂O₃ and FeOCl are considered to be present in the melt. In order to make dichloroethylene, HCl must be eliminated from the ethylene dichloride molecule. Both Fe₂O₃ and FeOCl will convert HCl to water. Consequently, the presence of Fe₂O₃ (an HCl acceptor) aids splitting out HCl and converting HCl to water.

In a bath process, the Fe₂O₃ is added in a specified amount to saturate the melt or it is generated in situ by oxidation of FeCl₂ in a partially reduced melt. In a continuous process where oxidation is being carried out at all times, the melt may contain some Fe₂O₃ produced by the following equation:

The amount of Fe₂O₃ that can be added to the melt to absorb HCl can be as much as 5 mole percent of the melt, but a sacrifice in yield loss to CO and CO₂ is likely to occur. The saturation level generally ranges from 0.05 to 1 percent.

Another ingredient which may be added to the melt is alkali fluoride. The presence of alkali fluoride in the melt increases the product selectivity to dichloroethylene. The fluoride of iron (FeF₃) is more stable than the chloride of iron (FeCl₃). Consequently, the addition of small amounts of fluoride tends to tie up the ferric ion and, therefore, tends to impede the chlorination reaction. The presence of a little fluoride probably acts the same as the presence of an excess alkali chloride; it cuts down on the vapor pressure of the chlorine, makes the melt less reactive to ethylene, and reduces the amount of higher chlorinated products. The alkali fluoride may comprise up to 10 percent of the total alkali halide present in the melt. The suitable alkali fluorides are: sodium fluoride, potassium fluoride, and lithium fluoride.

It is pointed out that the process of this invention is directed to chlorinating "by means of" a melt (molten salts) as distinguished from chlorinating "in" the melt or molten salt. It is the melt itself which does the chlorinating in the process of this invention and not any other liquid or gaseous additives. The process is significantly different from chlorinating with elemental chlorine because elemental chlorine gives a random product distribution whereas the process of this invention is selective and produces high yields. Chlorinating by means of a melt provides additional significant advantages over the prior chlorination processes. There is a uniform temperature throughout the melt and, consequently, a uniform chlorination rate. There is no agglomeration of catalyst particles as in a fluidized bed. More complete chlorination rates are available due to the presence of massive amounts of the chlorinating composition in the melt. In short, the melt chlorination process of this invention provides a more effective means for chlorinating.

The invention is illustrated by the following examples. In the examples and elsewhere in the specification all parts, proportions and percentages of materials or components are in mole percent, based on the moles of melt.

EXAMPLE 1

Into a glass reactor containing 1.25 liters of a melt of 12 moles NaCl and 12 moles FeCl₃ were passed 4.0 moles of ethylene per hour. The melt was mechanically stirred at a temperature of 295°C., under atmospheric pressure. Approximately 20 mole percent of the ethylene fed was converted to chlorohydrocarbons with about 69 percent of the chlorohydrocarbons being chloroethylenes (vinyl chloride, dichloroethylene, trichloroethylene and perchloroethylene). A summary of results at various oxidation levels (i.e., the fraction of iron chloride which is present as ferric chloride) is reported in Table I.

EXAMPLE 2

This example illustrates the importance of agitation (gas dispersion) upon substitutive chlorination of ethylene using the melt described in Example 1. The same process was carried out but at a temperature of 345°C. The comparison between a mechanically stirred and unstirred melt is shown in Table I.

When the melt reached the 82 percent oxidation level, the reaction was stopped by cutting off the ethylene feed. Then hydrogen chloride and oxygen were passed into the glass reactor to regenerate the melt to a 99 percent oxidation level; water was condensed as a by-product. This illustrates a step-wise regeneration procedure in a single reaction zone.

EXAMPLE 5

10 Into a glass reactor containing 0.65 liter of a melt of 10 moles LiCl and 10 moles FeCl₃ was passed 2.2 moles of ethylene per hour. The chlorination process was operated at a temperature of 275°C., at atmospheric pressure while the melt was mechanically stirred. Approximately 3 mole percent of the ethylene fed was converted to chlorohydrocarbons with about 67 percent selectivity to chloroethylenes. The results are reported 15 in Table I. It can be seen that the use of 100 percent LiCl as the alkali produced higher chlorinated products than the desired dichloroethylene.

TABLE I

Explanation of Abbreviations:

ViCl	- vinyl chloride
EtCl	- ethyl chloride
DCE	- dichloroethylene
EDC	- ethylene dichloride
TRI	- trichloroethylene
β-TRI	- 1,1,2 trichloroethane
PER	- perchloroethylene
TETRA	- tetrachloroethane
HEXA	- hexachloroethane

*Stirred

**Unstirred

EXAMPLE 3

This example illustrates the effect of varying the ratio of sodium chloride to ferric chloride in accordance with the procedure used in Example 1. At a temperature of 340°C., the results obtained from using a NaCl-/FeCl₃ ratio of 1.1:1 and 1.3:1, respectively, are shown in Table I.

EXAMPLE 4

Into a glass reactor containing 2.25 liters of a melt of 18 moles potassium chloride and 18 moles ferric chloride were passed 2.2 moles of ethylene per hour. The reaction was run at a temperature of 350°C. at atmospheric pressure while the melt was mechanically stirred. Approximately 14 mole percent of the ethylene fed was converted to chlorohydrocarbons with about 70 percent selectivity to chloroethylenes. The results are tabulated in Table I.

EXAMPLE 6

50 This example illustrates steady state chlorination of ethylene to dichloroethylenes with simultaneous regeneration of the melt with oxygen and hydrogen chloride in a zoned single reactor.

55 Into the glass vessel such as that illustrated in FIG. 1, containing 1.7 liters of a melt consisting of 16.2 moles (2625 grams) ferric chloride, 8.1 moles (604 grams) potassium chloride, and 8.1 moles (473 grams) sodium chloride, were passed 2.7 moles ethylene, 2.7 moles hydrogen chloride, and 0.8 mole oxygen per hour. Ethylene was fed through inlet 1 into zone A, while oxygen and hydrogen chloride were premixed and fed through inlet 2 into zone B at atmospheric pressure. The gases were disposed through porous glass frit 3. The temperature of the melt was determined with thermocouple 4 to be 335°C. After steady state was achieved at an 85 percent oxidation level, a gaseous effluent was withdrawn through scrubber 5. About 11 mole percent of

the ethylene fed was converted to chlorohydrocarbons with an 82 percent selectivity to chloroethylenes; 3.7 percent of the converted ethylene reacted to form CO and CO₂, providing a product yield of 75 percent. Also, 94 percent of the supplied oxygen was used (reacted) and the HCl content of the residual HCl/water phase was 71 weight percent. The isomeric dichloroethylenes comprised about 73 mole percent of the chlorohydrocarbon fraction as shown below:

Vinyl chloride	0.3 mole %	10
Dichloroethylene	73.0 mole %	
Trichloroethylene	7.5 mole %	
Perchloroethylene	0.7 mole %	
Ethyl chloride	1.1 mole %	
Ethylene dichloride	15.4 mole %	15
1,1,2-trichloroethane	0.7 mole %	
Sym. tetrachloroethane	0.9 mole %	
Pentachloroethane	0.1 mole %	
Chloral	0.3 mole %	
	100.0 mole %	

EXAMPLE 7

This example illustrates steady state chlorination of ethylene dichloride to chloroethylenes with simultaneous regeneration of the melt with oxygen and hydrogen chloride in a zoned single reactor.

To the same melt and reactor described in Example 6 were fed 2.8 moles ethylene dichloride, 2.7 moles hydrogen chloride and 0.7 mole oxygen per hour. Pre-heated ethylene dichloride vapors were fed through inlet 1 into zone A, while oxygen and hydrogen chloride were premixed and fed through inlet 2 into zone B at atmospheric pressure. At 345°C. after steady state was achieved at an 87 percent oxidation level, about 22 mole percent of the ethylene dichloride was converted to higher chlorohydrocarbons with about a 95 percent selectivity to chloroethylenes; 3.5% of the converted ethylene dichloride reacted to form CO and CO₂, providing a product yield of 86 percent. Also, 92 percent of the supplied oxygen was used (reacted) and the HCl content of the residual HCl/water phase was 91 weight percent. The isomeric dichloroethylenes comprised about 81 percent of the chlorohydrocarbon fraction as shown below:

Vinyl chloride	1.0 mole %	45
Dichloroethylene	80.7 mole %	
Trichloroethylene	13.0 mole %	
Perchloroethylene	2.1 mole %	
1,1,2-trichloroethane	1.4 mole %	
Sym. tetrachloroethane	1.1 mole %	
Chloral	0.7 mole %	
	100.0 mole %	

EXAMPLE 8

This example illustrates steady state chlorination of ethylene dichloride to dichloroethylenes with simultaneous regeneration of the melt with chlorine in a zoned single reactor.

To 5.5 liters of a melt consisting of 46.7 moles (7560 grams) ferric chloride, 23.4 moles (1745 grams) potassium chloride and 23.4 moles (1368 grams) sodium chloride contained in the glass vessel of FIG. 1 were passed per hour 7.0 moles ethylene dichloride and 5.2 moles chlorine per hour. Ethylene dichloride vapors were fed through inlet 1 into zone A, while chlorine was fed through inlet 2 into zone B at atmospheric pressure. At 350°C. after steady state was achieved at an 86

percent oxidation level about 60 mole percent of the ethylene dichloride fed was converted to other chlorohydrocarbons with about a 99 percent selectivity to chloroethylenes. The isomeric dichloroethylenes comprised about 87 percent of the chlorohydrocarbon fraction as shown below:

Vinyl chloride	2.3 mole %
Dichloroethylene	86.9 mole %
Trichloroethylene	8.5 mole %
Perchloroethylene	1.0 mole %
1,1,2-trichloroethane	0.6 mole %
Sym. tetrachloroethane	0.7 mole %
Chloral	0.0 mole %
	100.0 mole %

EXAMPLE 9

This example illustrates steady state chlorination of ethylene dichloride to dichloroethylenes with simultaneous regeneration of the melt with chlorine in an unzoned single reactor.

Into the glass vessel of FIG. 2 containing 2.8 liters of a melt consisting of 27.0 moles (4380 grams) ferric chloride and 27.0 moles (1578 grams) sodium chloride, were passed 4.1 moles ethylene dichloride, 2.5 moles chlorine and 0.2 mole hydrogen chloride per hour. The ethylene dichloride was vaporized and introduced through inlet 6 while the chlorine and hydrogen chloride were introduced through inlet 7 at atmospheric pressure. The gases were dispersed through porous glass frit 8. The temperature of the melt was determined with thermocouple 9; at 345°C. after steady state was achieved at an 81 percent oxidation level, a gaseous effluent was withdrawn through scrubber 10. About 52 mole percent of the ethylene dichloride fed was converted to other chlorohydrocarbons with about a 96 percent selectivity to chloroethylenes. The isomeric dichloroethylenes comprised about 75 mole percent of the chlorohydrocarbon fraction as shown below:

Vinyl chloride	5.8 mole %
Dichloroethylene	75.3 mole %
Trichloroethylene	11.1 mole %
Perchloroethylene	4.1 mole %
1,1,2-trichloroethane	1.2 mole %
Sym. tetrachloroethane	1.9 mole %
Chloral	0.6 mole %
	100.0 mole %

EXAMPLE 10

This example illustrates chlorination of ethylene to dichloroethylenes with subsequent regeneration of the melt with oxygen and hydrogen chloride in an unzoned single reaction.

Into the glass vessel of FIG. 3, containing 1.8 liters of a melt consisting of 15 moles (2433 grams) ferric chloride and 15 moles (1119 grams) potassium chloride, were passed 2.7 moles ethylene per hour. The ethylene was fed through inlet 11 beneath vane-disc agitator 12 rotating at 1200 RPM. The temperature of the melt was determined with thermocouple 13. At 379°C., a total of 3.6 moles of ethylene was fed over a period of 80 minutes. A gaseous effluent was withdrawn through scrubber 14. About 32 mole percent of the ethylene fed was converted to chlorohydrocarbons with a 90 percent selectivity to chloroethylenes. The isomeric dichloro-

ethylenes comprised about 69 mole percent of the chlorohydrocarbon fraction as shown below:

Vinyl chloride	17.3 mole %
Dichloroethylene	68.8 mole %
Trichloroethylene	3.8 mole %
Perchloroethylene	0.4 mole %
Ethyl chloride	2.5 mole %
Ethyl dichloride	6.7 mole %
1,1,2-trichloroethane	0.3 mole %
Sym. tetrachloroethane	0.1 mole %
Pentachloroethane	0.0 mole %
Hexachloroethane	0.0 mole %
Chloral	0.1 mole %
	100.0 mole %

The oxidation level of the melt was reduced from 100 to 72 percent.

The ethylene feed was shut off and the melt was reoxidized with oxygen. At 375°C., while stirring at 1200 RPM, oxygen was fed through feed 11 at the rate of 1.1 moles per hour. After feeding 1.2 moles oxygen, the melt oxidation level had been raised from 72 to 100 percent and iron oxides were found in the melt equivalent to oxygen consumed.

The oxygen feed was shut off and the melt was treated with hydrogen chloride. At 375°C. while stirring at 1200 RPM, hydrogen chloride was fed through feed 11 at the rate of 2.9 moles per hour. After feeding 5.8 moles of hydrogen chloride, a total of 2.1 moles of water had distilled from the melt through scrubber 14 with complete conversion of iron oxides to iron chloride.

EXAMPLE 11

This example illustrates the chlorination of ethylene in one reactor with concurrent regeneration of the melt with hydrogen chloride and oxygen in another reactor. Melt was circulated between reactors. Products were removed separately from each reactor.

Into zone A of the glass vessel of FIG. 4, containing 2.3 liters of melt consisting of 22.5 moles (3650 grams) ferric chloride and 22.5 moles (1675 grams) potassium chloride was passed 4.9 moles of ethylene per hour. Ethylene was fed through inlet 15 into zone A while hydrogen chloride and oxygen were fed through inlet 16 into zone B. Zone B also contained 2.3 liters of melt consisting of 22.5 moles (3650 grams) ferric chloride and 22.5 moles (1675 grams) potassium chloride. Into zone B were passed 4.9 moles oxygen and 7.3 moles hydrogen chloride per hour at atmospheric pressure. Constant speed paddle agitators 17 dispersed the gases in the melt. The melt was circulated between zones A and B via gas lift pumps 18. Thermocouples which were used to determine melt temperatures are not shown in this figure. At 352°C. and after steady state was achieved at 85 percent oxidation level in zone A and 91 percent oxidation level in zone B. About 22 mole percent of the ethylene fed was converted to chlorohydrocarbons with about an 80 percent selectivity to chloroethylenes. The isomeric dichloroethylenes comprised about 71 percent of the chlorohydrocarbon fraction as shown below:

Vinyl chloride	6.3 mole %
Dichloroethylene	71.3 mole %

-Continued

5	Trichloroethylene	3.2 mole %
	Perchloroethylene	0.0 mole %
	Ethyl chloride	0.7 mole %
	Ethylene dichloride	16.5 mole %
	1,1,2-trichloroethane	1.0 mole %
		100.0 mole %

Much modification and optimizing of process parameters can be carried out in addition to those described in the above examples. For example, the selective process of producing dichloroethylene can be carried nearly or close to 100 percent conversion by properly adjusting the temperature, oxidation level and feed rate of the process. Also, high yields (e.g., with minimum side reaction products such as CO and CO₂) can be obtained by selecting the proper melt composition, operating at optimum temperatures and utilizing preferred feed compositions.

Many statements of theory and suggested reasons for various reactions are given throughout the specification. However, this invention is not intended to be based on any particular theory or limited to any such reasons. The theory has been given mainly to aid in understanding the processes of this invention but in no way to limit or restrict the scope of this invention except as set forth in the claims.

What is claimed is:

1. A chlorination process consisting essentially of chlorinating a material selected from the group consisting of ethylene, ethylene dichloride, vinyl chloride and mixtures thereof to produce a chlorinated product which contains at least 50 mole percent of dichloroethylene, in a reaction zone, which is essentially free of elemental chlorine at a temperature within the range of 35 from 200°-450°C., by means of a melt comprising iron chloride and alkali metal chloride by dispersing the material to be chlorinated in the melt, the melt being the continuous phase, whereby said material is chlorinated by the melt; withdrawing a gaseous effluent from the reaction zone which contains unreacted starting material and the resulting chlorinated hydrocarbon products and recovering the chlorinated hydrocarbon products from the effluent as the products of the process; wherein:
  - a. the alkali metal chloride is selected from the group consisting of sodium chloride, potassium chloride, a mixture thereof, a mixture of sodium chloride and no more than 20 mole percent lithium chloride, a mixture of potassium chloride and no more than 20 mole percent lithium chloride, and a mixture of sodium chloride, potassium chloride and no more than 20 mole percent lithium chloride;
  - b. the mole ratio of alkali metal chloride to iron chloride is from about 0.5:1 to about 2:1; and
  - c. 60-90 mole percent of the iron chloride is maintained as ferric chloride.
2. A process in accordance with claim 1 wherein the melt also contains a member of the group consisting of Fe₂O₃, FeOCl, alkali metal fluorides, and mixtures thereof.
3. The process of claim 1 wherein the melt is regenerated with a combination of an oxygen-containing gas and hydrogen chloride.
